UNITED STATES PATENT OFFICE.

THOMAS COSSAR, OF GOVAN, SCOTLAND.

PRINTING-MACHINE.

SPECIFICATION forming part of Letters Patent No. 699,946, dated May 13, 1902.

Application filed October 20, 1899. Serial No. 734,165. (No model.)

To all whom it may concern:

Be it known that I, THOMAS COSSAR, a citizen of the United Kingdom of Great Britain and Ireland, residing at 6 Osborne Place, Govan, county of Lanark, Scotland, have invented certain new and useful Improvements in Printing-Machines, of which the following is a specification, such as will enable others skilled in the art to which it appertains to make and use the same.

This invention, which relates to oscillating-cylinder printing-machines—*i. e.*, machines in which the cylinder prints on the backward and forward movement of the bed—has for its object to provide means for automatically and intermittently feeding the paper to be printed from a web instead of, as heretofore, in sheets.

The invention is illustrated by the accompanying drawings.

Figure 1 represents diagrammatically the general arrangement of the improvements as applied to a printing-machine of the kind referred to. Fig. 1^a is a transverse section of Fig. 1 through the vertical center of the same, and Fig. 1^b is a detail view of the grippers. Fig. 2 is a vertical section of the means for automatically feeding the paper from the web, this figure showing the relation of the several parts when the main frame is in a position about one-fourth of its entire movement from the mid-position shown in Fig. 1, toward the left. Fig. 2^a is a view similar to Fig. 2, showing the main frame in a position on the other side of the mid-position of the machine. Fig. 3 is an elevation of the race for controlling the movements of a second frame carried by but independently movable upon the main frame. Fig. 3^a is a transverse section of Fig. 3 through the vertical center of the same. Fig. 4 is a view of the device for bringing the paper into register with the previous printing on its other side. Figs. 5 and 6 are respectively part elevations and cross-sections of a detail.

The oscillating cylinder A is fitted over the reciprocating type board or table B in the usual way, and under it is passed the end of a continuous web or roll C of paper, which is led from the roll D first between a pair of feeding-rollers E, which pull the paper off the roll D at the proper speed, then around a

tension-roller F, which takes up the slack caused by the to-and-fro movement of the gripper-frame, then over a guide-roller F² and horizontally between a set of grippers G', comprising a grip-bar and gripping-fingers, of which latter there may be any number strung on a rod extending between the sides of the frame G, the grippers being carried in the traveling frame G, the parts of which are hereinafter described, thence over a roller H', situated beyond the grippers G', referred to, and carried in the same traveling frame G in the same horizontal plane back and around a roller J, situated behind and lower than the grippers G' when the traveling frame G is in the position shown at Fig. 1. This latter roller J is attached to a frame I, carried in the before-mentioned traveling frame G by mechanism hereinafter particularly described, to effect the pulling through of the web C when the cylinder A is clear of the printing form or table B at each end of the stroke of the printing-machine and at other times, as hereinafter described. The web C is then carried back again in its original direction around a roller H², beneath the roller H', then between a second set of grippers G², situated immediately below the first-mentioned grippers G' and carried in the same traveling frame G, thence around one or more guide-rollers K and under the printing-cylinder A, the web being thereafter carried around guide-rollers K', grippers G³ G⁴, and rollers H³ J' H⁴, similar in number and arrangement to those before mentioned and carried in the same frame G, and thence over a guide-roller F³ and tension-roller F' and between a pair of feeding-rollers E', as shown, revolving at the proper speed, being geared to the feed-rolls E and forward to a folder or cutting device, or it may be taken to a spindle D', on which it is wound again. The paper C is thus doubled on itself twice before being led under the cylinder A and again doubled on itself twice after leaving the cylinder. The feeding of the paper C is effected by the combined action of the grippers G' G² G³ G⁴, the rollers E and E', previously referred to, and the rollers J J', carried in the frame I, which engage with the proper portions of the web at the proper times, the grippers being carried in the traveling frame G, before mentioned, and

which is operated by means of a rack G^5 , secured to it, gearing with a toothed wheel L , receiving its motion through bevel-wheels M M' M^2 or by sprocket-gearing from the oscillating cylinder A . The gripping device is formed by the frames G , situated on either side of the printing-machine within the stationary frames x and guided thereon, the frames G being tied together by rods g , extending transversely of the machine and capable of turning, which rods in conjunction with pivoted fingers constitute the grippers which hold the web C when these act to feed the necessary length of paper. The grippers are caused to grip the paper by means of springs g' , such as shown, acting on projections g^2 on the rods g , or coiled springs wound around the rods g and secured thereto and to the frame G may be employed, and these springs are caused to release the paper by the action of projections x' on the stationary frame x upon arms N , keyed on the gripper-rods, the grippers $G' G^2$ being actuated by those on one side frame and the grippers G^3 G^4 by those on the other side frame. The second frame I , which consists merely of two bars, each having one end of each of the rollers $J J'$ centered in it, is guided in bearings I^1 in the first or traveling frame, as shown in Fig. 1^a, and has its movement imparted to it, as shown particularly at Fig. 2, by racks I' , formed on or secured to each bar, and toothed wheels I^2 , gearing with these racks, and a toothed wheel I^6 on the shaft I^8 , carrying these gear-wheels I^2 , is actuated by a toothed quadrant-arm I^4 , a roller I^5 the end of which travels in a race O , carried by the stationary framing x , and shown particularly at Fig. 3, and consisting of inclined and horizontal portions forming forward and return passages crossing each other centrally to give to the quadrant-arm I^4 the necessary movement to give the rollers $J J'$ their proper length of stroke, according to the size of sheet being printed. This race O , which is supported from the framing at its mid-point, which is stationary, by brackets, (not shown,) and also at the stationary portions of its ends, as hereinafter described, is provided at various points with spring-catches O^{13} , located in pockets or recesses in the back part of the guide-frame O^{14} , as shown in Figs. 5 and 6, which spring-catches yield to allow the roller I^5 to pass in one direction, but prevent its passage in another direction. These spring-catches consist, preferably, of blocks fitted in pockets O^{15} in the race O and pushed outward by springs O^{16} , these blocks being inclined at their outer ends, so that by the action upon them of the roller I^5 , which travels in the direction of the arrows, Fig. 5, the blocks permit of the passage of said roller I^5 and spring out again behind it, thereby preventing its movement other than in the proper direction on the reversal of the motion of the frame G . The central portion O' of the race is preferably pivoted on a stud L' , by which the race O is carried from a

bracket L^2 , secured to the machine-framing X , as shown at Figs. 1^a and 3^a, so that portion O' can be turned to guide the roller I^5 on quadrant-arm I^4 in either direction at the proper time according as the roller I^5 is on its forward or return movement, and instead of the spring-catches O^{13} part of the end portions O^2 of the race can be pivoted on the studs L^3 , which support the ends of the race from the machine-framing, and worked simultaneously with the central portion O' by means of levers O^6 and connecting-rods O^7 , the central portion O' being actuated from a connecting-link O^9 , a slotted lever O^{10} , and from a rod O^{11} from a cam O^{12} on any motion-shaft, as shown at Fig. 3, preferably a shaft having a half-revolution for each copy printed. By altering the position of the rod O^9 to the other end of the slotted lever O^{10} the general or ultimate direction of the feed of the web C is reversed. By "ultimate direction" is meant that while that portion of the web under the influence of the grippers undergoes a series of movements in opposite directions its ultimate direction is toward the winding on spindle D' . The guide-race O can be altered somewhat in form for the purpose of shortening or lengthening the stroke of the quadrant-arm I^4 , this being effected by means of screw-threaded spindles O^8 , attached to the movable portions of the race and which may be actuated by worm-wheels O^4 , portions of the race being secured to or formed upon nuts O^9 , secured to the central and end portions by strips O^{14} , also forming portions of the race, the nuts O^9 embracing the screw-threaded spindles O^8 and being guided in frames O^6 . For this purpose a sufficient length of slot is left in the rotatable end portions O^2 of the race to suit any length of movement of the frame G . The nuts O^9 are moved upward or downward upon the screw-threaded spindle by means of the worm-wheels O^4 on their ends, these wheels O^4 being actuated by worms P on a shaft P' , which can be turned by hand in order to alter the distance apart of the nuts O^9 , and consequently the stroke of the quadrant-arm I^4 , to suit the size of sheet being printed. One set of grippers engages a length of the web C on one side of the cylinder A and feeds it forward as the cylinder revolves, while another set of grippers simultaneously engages a length on the other side and draws it off in the same direction. The to-and-fro movement of the gripper-frame G in unison with the oscillations of the cylinder A is effected by imparting a rocking motion or alternately right and left hand movement of rotation to the sprocket or toothed wheel shaft gearing with the racks G^5 by gearing it with the racks on bed of the printing-machine, or the frame G may, as shown and described, be geared to the cylinder A .

The cylinder A acts to press the paper onto the type or blocks on the board or table B and effects a printing at each oscillation, and a sufficient length of the web C is fed forward

at one action of the grippers to provide for one print as the cylinder A oscillates with the paper under it. Then a length of paper sufficient for another print is drawn off after 5 the cylinder is clear of and before it again touches the form or board B in its return oscillation, this length being fed through and printed on the return stroke of cylinder A. Then this printed portion is drawn through 10 after the cylinder A is clear of and before it again touches the form B in its next oscillation, and a further length is fed through and printed during the forward oscillation of the cylinder, and the two rollers J J', carried in 15 the second frame I, which is carried by the first or traveling frame G, being actuated to pull through the web C when the cylinder A has cleared the printing-form B.

The table B of the machine being in its 20 mid-position and the frame G also in mid-position, as shown at Fig. 1, the table B is printing and is moving from left to right, the frame G moving at the same time from right to left—that is to say, the cylinder and table are both on the backward movement. The two lower sets G² G³ of the grippers are now closed and the top sets G' G⁴ of grippers are open, the former sets carrying the web C along as it is printed at the same speed as the 25 surface speed of the cylinder and table. The cam-roller I⁵, working in the race O, is during this motion of the frame G moved down to the position shown at Fig. 2, thus moving through the gearing and rack the intermediate rollers J J' to the right, thereby pulling a new part of web C from the roller D. When the cam-roller I⁵ has reached its lowest point in the race O—i. e., the position indicated on Fig. 2—the arms N of the grippers G' G⁴, at present open, having now reached the end of their respective projections x', slip clear of these projections and close under the action of their springs, the grippers G² G³, previously closed under the 30 action of their springs, now opening under the action of their projection x'. The type on the table B has now cleared the cylinder A, and during the remainder of the movement of the main frame G from right to left, 35 in which the grippers G' G⁴ remain closed and the grippers G² G³ remain open, the movement of the frame I from left to right ceases, and, excepting for an infinitesimal period of time, for which the nut O⁸ is responsible, 40 (this horizontal portion O⁸ having a function hereinafter explained,) said frame I is traversed from right to left under the action of the quadrant-lever I⁴, the roller of which is during this period rising in the race O. The frame I on being traversed in this direction pulls through that portion of the web first printed and brings down part of a new length to be printed on the movement of the printing-table from right to left—i. e., the forward movement—this pulling action being half completed when the roller I⁵ and quadrant I⁴ have 45 reached the position indicated on Fig. 2^a in dotted lines and marked 2. The printing-table B is now beginning its return movement and the frame G its corresponding return movement, (both moving always in opposite directions,) the roller I⁵ still farther ascending along the slot in the race O, whereby because of the continued rotation of the quadrant I⁴ in this direction the rollers J J' are caused to pull 50 through the remaining length of web, which, along with the new length already pulled through, forms the size of sheet to be printed, the frame I having now reached its extreme left-hand movement. (Indicated by 3, Fig. 2.) 55 The open sets G² G³ of grippers, owing to the roller I⁵ having reached the position indicated in dotted lines at Fig. 2^a and marked 3, have now returned along their projections and almost cleared these, will immediately close, 60 and the previously-closed sets G' G⁴ of grippers will on coming into contact with their projections open, and the cam-roller I⁵, having reached the end of the horizontal part O⁸, will begin to descend the slot in the race 65 O. The frame I will then move in the same direction as the frame G and the roller J and pull another length from the web C, the tension-roller F' taking up the slack, which at this moment by the lessening of the length of 70 the loop over the roller J', as shown at Fig. 2^a, is formed quicker than the winding on spindle D' is designed to take it up, the closed set G² G³ of grippers carrying through the desired length of web along with the cylinder 75 while it is printing. When the cam-roller I⁵ has reached the position shown at 4, Fig. 2^a, the type-table having cleared the cylinder and the open grippers G' G⁴ having cleared their projections, these grippers are then 80 closed, and the closed grippers G² G³ having engaged their projections are opened and the cam-roller I⁵ begins to ascend, causing the frame I to move in the opposite direction to the motion of the frame G, and consequently 85 causing the intermediate roller J' to pull a new length of web through below the cylinder A to be printed on the motion of the printing form or table B back again from left to right. 90

The catches O¹³ or the pivoted portions in the race are altered at the proper times, the former by removing the inclined yielding portions from their recesses in the race and inserting them with their inclined edges in the 95 contrary direction to suit the direction of travel of the roller I⁵, and the latter by the mechanism already referred to and the times at which these movements take place may be altered by adjustment of the link O⁹ in the 100 slot of the lever O¹⁰ in order to cause the quadrant-arm I⁴ to take a downward instead of, as formerly, an upward path, and go upward, when before it went downward, and thus alter the general or ultimate direction 105 of the feed of the web C should circumstances make such alteration necessary. The grippers are opened and closed when the cam-roller I⁵ is in either of the horizontal portions 110

of the race—*i. e.*, in the nuts O^8 —in order that no shifting of the web beneath the grippers shall take place at that time.

A pair of rollers Y , situated above the oscillating cylinder A , each carrying a portion of the web C on the opposite side of the cylinder A from the other, are carried in a movable frame Y' , such as shown at Fig. 4, supported by screw-threaded rods Y^2 , carried on the machine-frame x , these rods Y^2 passing through nuts Y^3 , formed on the movable frame Y' , the rods Y^2 being capable of operation by hand or otherwise, so as to cause the roller on one side of cylinder A to move toward the cylinder to shorten the path of web on that side of the cylinder while the roller on other side of cylinder lengthens the path of the web on its side of cylinder A , or vice versa, and thus shift the web in one direction or the other when printing on second side of web, so as to register the second printing with the first.

A cone-pulley Q is provided on a shaft driven by the machine, and a similar cone-pulley Q' on a shaft geared to the two pairs of feeding-rollers E , as previously mentioned, the large end of one cone-pulley being opposite the small end of the other, the rollers E being geared to the shaft carrying the second cone-pulley by a shaft U and bevels $U' U^2 U^3$, the latter wheels $U^2 U^3$ being so placed in relation to the wheels on the roller E that by operating a clutch between these the direction of rotation of the rollers E may be changed when desired according to the general or ultimate direction of feed of web without altering the direction of rotation of second cone-pulley. The belt R , which connects the two cones, is shifted along the cones $Q Q'$ in one direction or the other by forks S , actuated by a screw-threaded spindle T , according to the rate of feed which is required.

Having now described the invention, what I claim, and desire to secure by Letters Patent, is—

1. In an oscillating-cylinder printing-machine, means for automatically and intermittently feeding the paper to be printed from the web, consisting of a sliding frame, a rack on said frame geared to a driven toothed wheel, spring-grippers for engaging the paper, and a second independently movable frame carried by the first-mentioned frame, substantially as shown and described.

2. In oscillating-cylinder printing-machines for printing from the web, the combination with a sliding frame, of a second frame carried by said sliding frame, gear-wheels centered on the sliding frame engaging racks on the second frame, a quadrant-arm for actuating said gear-wheels, and a race which controls the movement of said quadrant-arm, substantially as shown and described.

3. In oscillating-cylinder printing-machines for printing from the web, the combination with a quadrant-arm, of a race for controlling the movement of said quadrant-arm, said race being jointed and adjustable by the action of screwed spindles upon nuts on the race, to lengthen or shorten the path of the quadrant-arm controlled by the race, substantially as shown and described.

4. In oscillating-cylinder printing-machines for printing from the web, the combination with a quadrant-arm, of means for altering the direction of movement of the quadrant-arm and ultimate direction of the feed consisting of levers connected to the pivoted portions of the race, rods connecting these levers together, a rod connecting one of the pivoted portions to a slotted quadrant and a second rod connected to said quadrant and carrying a roller operated by a cam, substantially as shown and described.

In witness whereof I have hereunto set my hand in presence of two witnesses.

THOMAS COSSAR.
